UNITED STATES PATENT OFFICE.

JEREMIAH E. LANGFORD, OF SALT LAKE CITY, UTAH.

RAILROAD-TIE AND RAIL-GRIP.

1,227,636.

Specification of Letters Patent. Patented May 29, 1917.

Application filed June 3, 1916. Serial No. 101,469.

To all whom it may concern:

Be it known that I, JEREMIAH E. LANGFORD, a citizen of the United States, residing at Salt Lake City, in the county of Salt Lake and State of Utah, have invented a new and useful Railroad-Tie and Rail-Grip, of which the following is a specification.

My invention relates particularly to ties adapted to be used in railroads and provided with means for securing the rails thereto. It has special reference, however, to metallic ties and particularly steel ties designed for this purpose.

15 The object of my invention is to provide a railroad tie and rail grip which may be used on earth or gravel beds, in concrete constructions, on paved streets, on wooden wharves or trestles, as well as steel constructions such, for example, as bridges.

A further object of my invention is to provide a rail tie and gripping means which is adapted to hold the rails in place without the necessity of applying any railway 25 spikes.

A further object of my invention is to provide a metallic railway tie which is so arranged as to effectively insulate the two rails from each other so as to avoid any 30 interference with signaling devices which are dependent upon the closing of an electric circuit between the two rails as, for example, through the wheels and axles of a car passing over the rails.

35 A further object of my invention is to provide a construction of this kind in which the portions of the tie subjected to the greatest stress are made exceptionally strong so as to adequately support the rails and 40 the loads carried by the same. This form of construction enables the remainder of the tie to be made without the presence of an excessive amount of metal in the body of the tie.

45 A further object of my invention is to provide a construction in which the two ends of the tie are insulated from each other so that the electrical connections at the two ends of the tie may be independent 50 of each other. This permits, if desired, the omission of any insulation between the rail and the tie under certain conditions. Another object of my invention is to provide a rail-tie, the two ends of which are flexibly connected to each other so that one end

of the tie may give without affecting the stability or rigidity of the other end of the tie.

A further object of my invention is to provide a railroad tie of this kind which is exceedingly simple and which is, nevertheless, very strong in construction.

While my invention is capable of embodiment in many different forms, for the purpose of illustration I have shown only one form thereof in the accompanying drawings, in which,

Figure 1 is a plan view of a railroad constructed in accordance with my invention;

Fig. 2 is a cross-section of the same;

Fig. 3 is a plan view of a rail and gripping means partly in section;

Fig. 4 is an end elevation of the gripping means;

Fig. 5 is a cross-section of a tie with the rail in place;

Fig. 6 is a cross-section taken through the central joint between the two ends of the tie; and

Fig. 7 is a view similar to Fig. 4, but showing a solid plate and not carrying insulation for securing the rail in the tie.

In the drawings, I have shown a railroad tie 1, comprising two halves 1^a and 1^b, each of which is in the shape of a channel bar. That is to say, each comprises a base 2 and two lateral, upwardly directed flanges 3. The half 1^a is provided at its inner end with a double bar 3^a, which may be attached at its ends to the half 1^b by means of spot welding or in any other suitable manner. The double bar 3^a has an opening 3^b through which passes an insulating sleeve 3^c, which receives a bolt 3^d for securing the bar 3^a to two bars 3^e attached to the half 1^b by spot welding or in any other suitable manner. On the inside and outside of each of the bars 3^e there are provided insulating washers 3^f. The base 2 is preferably provided with an opening 4 to properly anchor the tie to the roadbed. In the case of earth or gravel roadbeds, the earth or gravel passing through the openings 4 and resting upon the top of the base 2 will effectively anchor the tie in place. Furthermore, the narrow width of the tie at the center will enable the earth or gravel surrounding the tie to prevent longitudinal movement of the tie. Where the tie is used upon trestles or bridges, and where the tie is to be attached to longi-

tudinal stringers, spikes or bolts may be passed through the opening 4 to attach the tie to the same. The flanges 3 have beveled ends 5 to prevent injury to workmen when 5 laying or repairing the railroad. As shown in Fig. 2 the tie 1 is arranged to support a plurality of rails 6 of the usual form in cross-section. Each of these rails 6 is supported in a pair of inner grip plates 7 so arranged 10 as to leave openings 8 between the grip plates 7 and the edges of the rail, so as to produce a wedging grip upon the base of the rail, when it is placed in position in the manner hereinafter described. The inner 15 grip plates 7 rest against plates or strips 9 of fiber or other electrically insulating material, and the strips or plates 9 in turn rest within outer grip plates 10. The outer grip plates 10 are tapered so as to be thinner at 20 one end than the other, so that they may act as wedges when being inserted in the ties to hold the rails in place. Preferably the grip plates 7 and 10 and the insulating plates or strips 9 are cemented together with 25 any suitable cement. If desired also the grip plates 7 and 10, and the insulating plates or strips 9 may be connected together by insulating fiber rivets 11. If desired, instead of the inner and outer grip plates 7 and 10 and 30 the insulating strips 9, there may be provided solid tapered grip plates 12 as shown in Fig. 7. The lateral flanges 3 on the ties have recesses or openings 13 provided therein to receive the rails 6 and the grip plates. 35 Said openings 13 at their uppermost portions are substantially the width of the bases of the rails to be supported by the ties. Below the upper parts of these openings 13, however, the openings are widened in such 40 a manner as to receive the grip plates 7 and 10. Between the lateral flanges 3, and at either side of the openings 13, I provide a reinforcing plate 14, which is comprised of two laterally directed wings 14^a, which fit 45 against flanges 3 to which they may be secured by welding or in any other suitable manner and a cross web 14^b connecting the laterally directed wings 14^a together. The wings of the reinforcing plates 14^a may extend 50 along the flanges 3 to any desired length. These reinforcing plates have the effect of strengthening and stiffening the tie at the points where the stress is greatest, that is to say, immediately beneath the rails 55 which are supported by the tie. The openings 13 are, of course, made in such a way that the openings in one of the flanges 3 are a little wider than the openings in the other flange 3 in order to accommodate the tapering outer grip plates 10.

Railroads may be constructed primarily with ties of this character or they may be repaired by replacing other forms of ties with ties of this kind. Assuming that the railroad 65 is being built with ties of this kind, the

ties are placed at the proper intervals along the roadbed. The two halves 1^a and 1^b of the ties are connected together by inserting bolts 3^d through the double bar 3^a and the two bars 3^e in such a manner that the insulating sleeves 3^c surround the bolts 3^d and the insulating washers 3^f remove said bolt from contact with the bars 3^a and 3^e, and the rails are then dropped into place in the openings 13. The inner grip plates 7 and 75 outer grip plates 10 and interposed strips of insulating material 9 which have been previously preferably attached together by means of cement insulating material, or fiber rivets, are now applied to the rails by insertion thereof between the edges of the bases of the rails and the wider portions of the recesses or openings 13, the thinner ends of the outer grip plates 10 being inserted first and the composite grip plates being then 80 driven in place until the wedging action of the grip plates on the bases of the rails tightly clamps the rails in place. Instead of using the grip plates comprised of the inner and outer plates 7 and 10, and the interposed insulating plates 9 the solid gripping plates 12 may be used. The reinforcing plates 14 adequately support the rails and the loads carried by the same, inasmuch as they surround the edges of the rail bases 85 which rest upon the ties, and as they reinforce the tie not only vertically and laterally along the flanges of the tie, but also longitudinally of the rail and vertically in a direction longitudinal of the rail by means 90 of the webs 14^b passing under the same. If the railroad is being laid along the ground or upon gravel, the roadbed is now filled with the earth or gravel up to the required level, and the ties are now securely held in place by this means. If on the other hand, the railroad is being laid along a trestle or on a bridge, fastening means may be applied through the openings 4 to securely hold the ties in place. The insulating sleeve 3^c and 95 the insulating washers 3^f will effectively insulate the two rails from each other. The two rails 6 will therefore be insulated from each other and signaling systems involving the completion of a circuit between the rails 100 when the train passes, will not be interfered with. The fact that the two ends 1^a and 1^b of the tie are pivoted together permits either end of the tie to give without affecting the rigidity or stability of the other end of the 105 tie.

While I have described my invention above in detail, I wish it to be understood that many changes may be made therein without departing from the spirit of my invention. For example, wherever I have shown rivets spot welding may be used for connecting the parts together instead.

I claim:

1. The combination of a channel shaped 110

- 5 railroad tie having recesses in its sides to receive a rail, with a reinforcing member conforming to the recesses and extending between the latter, said member being permanently fixed to the tie.
- 10 2. In combination, a railroad tie having a recess to receive a rail and a reinforcing means located at said recess, and following the contour of said recess.
- 15 3. In combination, a railroad tie having a recess to receive a rail, a tapering clamping means at the side of the rail, and a reinforcing means located at said recess, and extending longitudinally of the rail.
- 20 4. In combination, a railroad tie having a recess to receive a rail, a tapering clamping means at the side of the rail, and a reinforcing means located at said recess, and following the contour of said recess.
- 25 5. In combination, a railroad tie having a recess to receive a rail, a tapering clamping means at the side of the rail, comprising an inner and outer plate, and a reinforcing means located at said recess, and extending longitudinally of the rail.
- 30 6. In combination, a railroad tie having a recess to receive a rail, a tapering clamping means at the side of the rail, comprising an inner and outer plate, and a reinforcing means located at said recess, and following the contour of said recess.
- 35 7. In combination, a railroad tie having a recess to receive a rail, a tapering clamping means at the side of the rail, comprising an inner and outer plate separated by an insulating plate, and a reinforcing means located at said recess, and extending longitudinally of the rail.
- 40 8. In combination, a railroad tie having a recess to receive a rail, a tapering clamping means at the side of the rail, comprising an inner and outer plate separated by an insulating plate, and a reinforcing means located at said recess, and following the contour of said recess.
- 45 9. The combination of a channel shaped railroad tie having recesses in its sides to receive a rail, with reinforcing members comprising complementary plates shaped to conform to the recesses, and to extend between the same.
- 50 10. In combination, a U-shaped railroad tie having a recess to receive a rail and a reinforcing means located at said recess, and following the contour of said recess.
- 55 11. In combination, a U-shaped railroad tie having a recess to receive a rail, a tapering clamping means at the side of the rail, and a reinforcing means located at said recess, and extending longitudinally of the rail.
- 60 12. In combination, a U-shaped railroad tie having a recess to receive a rail, a tapering clamping means at the side of the rail, and a reinforcing means located at said recess.
- 65 13. In combination, a U-shaped railroad tie having a recess to receive a rail, a tapering clamping means at the side of the rail, comprising an inner and an outer plate, and a reinforcing means located at said recess, and extending longitudinally of the rail.
- 70 14. In combination, a U-shaped railroad tie having a recess to receive a rail, a tapering clamping means at the side of the rail, comprising an inner and an outer plate, and a reinforcing means located at said recess, and following the contour of said recess.
- 75 15. In combination, a U-shaped railroad tie having a recess to receive a rail, a tapering clamping means at the side of the rail, comprising an inner and an outer plate separated by an insulating plate, and a reinforcing means located at said recess, and extending longitudinally of the rail.
- 80 16. In combination, a U-shaped railroad tie having a recess to receive a rail, a tapering clamping means at the side of the rail, comprising an inner and an outer plate separated by an insulating plate, and a reinforcing means located at said recess, and following the contour of said recess.
- 85 17. In combination, a U-shaped railroad tie having a recess to receive a rail and a reinforcing means located at said recess, said reinforcing means comprising wings permanently attached to the flanges of the tie and a cross web connecting the wings.
- 90 18. In combination, a U-shaped railroad tie having a recess to receive a rail and a reinforcing means located at said recess, said reinforcing means comprising wings attached to the flanges of the tie and a cross web connecting the wings.
- 95 19. In combination, a U-shaped railroad tie having a recess to receive a rail, a tapering clamping means at the side of the rail, and a reinforcing means located at said recess, said reinforcing means comprising wings attached to the flanges of the tie and a cross web connecting the wings.
- 100 20. In combination, a U-shaped railroad tie having a recess to receive a rail, a tapering clamping means at the side of the rail, and a reinforcing means located at said recess, said reinforcing means comprising wings attached to the flanges of the tie and a cross web connecting the wings.
- 105 21. In combination, a U-shaped railroad tie having a recess to receive a rail, a tapering clamping means at the side of the rail, comprising an inner and an outer plate, and a reinforcing means located at said recess, said reinforcing means comprising wings attached to the flanges of the tie and a cross web connecting the wings.
- 110 22. In combination, a U-shaped railroad tie having a recess to receive a rail, a tapering clamping means at the side of the rail, comprising an inner and an outer plate, and a reinforcing means located at said recess, said reinforcing means comprising wings attached to the flanges of the tie and a cross web connecting the wings.

- tie having a recess to receive a rail, a tapering clamping means at the side of the rail, comprising an inner and an outer plate, and a reinforcing means located at said recess, and following the contour of said recess, said reinforcing means comprising wings attached to the flanges of the tie and a cross web connecting the wings.
23. In combination, a U-shaped railroad tie having a recess to receive a rail, a tapering clamping means at the side of the rail, comprising an inner and an outer plate separated by an insulating plate, and a reinforcing means located at said recess, said reinforcing means comprising wings attached to the flanges of the tie and a cross web connecting the wings.
24. In combination, a U-shaped railroad tie having a recess to receive a rail, a tapering clamping means at the side of the rail, comprising an inner and an outer plate separated by an insulating plate, and a reinforcing means located at said recess, and following the contour of said recess, said reinforcing means comprising wings attached to the flanges of the tie and a cross web connecting the wings.
25. In combination, a railroad tie having a recess to receive a rail and tapering clamping means at the side of the rail, comprising an inner and an outer plate separated by an insulating plate, said plates being united with fiber rivets.
26. In combination, a railroad tie having a recess to receive a rail, and clamping means at the side of the rail, comprising an inner and an outer plate separated by an insulating plate, said plates being united with fiber rivets.
27. A railroad tie comprising two halves, each of which is adapted to carry a rail, said halves being insulated from each other.
28. A railroad tie comprising two pivoted halves, each of which is adapted to carry a rail, said halves being insulated from each other.
29. A railroad tie comprising two halves, each of which is adapted to carry a rail, said halves being insulated from each other by means of an insulating bolt connecting said halves.
30. A railroad tie comprising two pivoted halves, each of which is adapted to carry a rail, said halves being insulated from each other by means of an insulating bolt connecting said halves.
31. A railroad tie comprising two halves, each of which is adapted to carry a rail, said halves being insulated from each other by means of an insulating bolt connecting said halves.

said halves, and supporting said halves by interposed washers and an insulating sleeve.

32. A railroad tie comprising two pivoted halves, each of which is adapted to carry a rail, said halves being insulated from each other by means of an insulating bolt connecting said halves, and supporting said halves by interposed washers and an insulating sleeve.

33. A railroad tie comprising two halves, each of which is adapted to carry a rail, each half having at its inner end bars bent toward each other, said halves being insulated from each other.

34. A railroad tie comprising two pivoted halves, each of which is adapted to carry a rail, each half having at its inner end bars bent toward each other, said halves being insulated from each other.

35. A railroad tie comprising two halves, each of which is adapted to carry a rail, each half having at its inner end bars bent toward each other, said halves being insulated from each other, by means of an insulating bolt connecting said halves.

36. A railroad tie comprising two pivoted halves, each of which is adapted to carry a rail, each half having at its inner end bars bent toward each other, said halves being insulated from each other by means of an insulating bolt connecting said halves.

37. A railroad tie comprising two halves, each of which is adapted to carry a rail, each half having at its inner end bars bent toward each other, said halves being insulated from each other by means of an insulating bolt connecting said halves, and supporting said halves by interposed washers and an insulating sleeve.

38. A railroad tie comprising two pivoted halves, each of which is adapted to carry a rail, each half having at its inner end bars bent toward each other, said halves being insulated from each other by means of an insulating bolt connecting said halves, and supporting said halves by interposed washers and an insulating sleeve.

39. The combination of a channel shaped railroad tie having recesses in its sides to receive a rail, with reinforcing members comprising complementary plates, each having a flange shaped to surround a portion of each recess, and a web uniting the flanges.

In testimony that I claim the foregoing I have hereunto set my hand.
